UNITED STATES PATENT OFFICE.

PERCIVAL H. FLOYD, OF DOUGLASTON, NEW YORK, ASSIGNOR TO WRIGHT & DITSON-VICTOR CO., OF NEW YORK, N. Y., A CORPORATION OF MASSACHUSETTS.

FOOTBALL SHOE.

Application filed February 26, 1926. Serial No. 90,910.

This invention relates to football shoes. It is the usual practice to secure a series of cleats on the bottom of a football shoe to prevent the player from slipping, or at least to reduce the tendency to slip. In playing on a wet field it is found that the bottom of a shoe so equipped loads up badly with mud. The mud packs in firmly between the cleats and renders them practically useless until it has been dislodged. This difficulty can be reduced somewhat by using an extra long cleat, commonly known as a "mud cleat", but these cleats are so long or "high" that they are not suitable for use on firm ground or turf. Consequently, a player shod with cleats of this kind and playing on a field which is muddy in some parts only, finds that while these cleats are very useful in the muddy parts of the field, they are a great handicap in playing on the portions of the field that are relatively firm and hard.

The present invention deals with the problem presented by these conditions, and it aims to devise a cleat arrangement which will not load up with mud sufficiently to interfere seriously with the function of the cleats, and which will be satisfactory on both a wet and a dry field.

The nature of the invention will be readily understood from the following description when read in connection with the accompanying drawings, and the novel features will be particularly pointed out in the appended claims.

In the drawings:—

Figure 1 is a perspective side view of a football shoe having a cleat arrangement embodying this invention; and Fig. 2 is a perspective view of the bottom of the shoe shown in Fig. 1.

It will be seen from an inspection of the drawings that the shoe shown is equipped with two types of cleats, some being of polygonal form in cross-section while others are of circular cross-section. It is preferable to use a tapered cleat and I prefer, also, to use cleats of rectangular outline in horizontal cross-section on some parts of the shoe. The latter cleats, therefore, have the form of the frustum of a pyramid, while the other cleats are of frusto-conical shape.

Referring to Fig. 2, which shows the bottom of a right shoe, it will be observed that the cleats on the sole of the shoe are ar-

ranged in two rows near opposite edges of the sole. The row along the inside edge includes two rectangular cleats 2 and 3 with a circular cleat 4 between them, while the row on the outer margin of the sole consists of two rectangular cleats 5 and 6 with a circular cleat 7 between them. Another rectangular cleat 8 is located near the extremity of the toe. Preferably the cleat 5 on the ball portion of the sole and the cleat 8 at the toe are located transversely to the longitudinal median line of the shoe, since this arrangement assists the player in starting and stopping, and the cleat 8 also is of great help in running. The other rectangular cleats 2, 3 and 6 all extend in a fore and aft direction, or longitudinally of the shoe, and are of particular value in pushing against the line or in shifting the direction to either the right or left while running.

On the heel of the shoe shown one rectangular cleat 9 is used at the back of the heel, and two circular cleats 10 and 12 are located near the opposite breast corners. The cleat 9 extends transversely to the longitudinal median line of the shoe and is of great assistance in running and in stopping.

All of the cleats preferably are of a height suitable for use on a dry field, say from one-half to three-quarters of an inch. It will be observed that the circular or frusto-conical cleats are so interspersed with the rectangular cleats that the adjacent surfaces of neighboring cleats do not present flat faces of substantial area in opposed contiguous relationship. In other words, the flat surfaces of the rectangular cleats are, in all cases except that of the cleat 8, opposed to the convex surfaces of the frusto-conical cleats. This arrangement appears to be responsible, at least in a large measure, for the extremely favorable results which have been found by experience to attend the use of this shoe on a muddy field. The mud does not pack in around the cleats and cling to them sufficiently to interfere seriously with their normal functions. On the contrary, the bottom of the shoe stays remarkably free from the accumulations of mud that have proved so troublesome heretofore. This cleat arrangement is also entirely satisfactory on turf or on a hard field.

It should be noted that in no case are there opposed flat surfaces of substantial area located so close to each other that the mud

could pack and wedge in between them to any substantial degree. While small portions of the rear side of the cleat 8 are in nearly opposed relationship to the forward ends of the cleats 3 and 6 on the toe portion of the shoe, still the entire central portion of the sole back of the cleat 8 is open or free, and the opposed surfaces just mentioned are so small, due to the tapered construction of the cleats, that no trouble is experienced with the loading up of the cleats with mud at these points.

The cleats shown are readily obtainable on the market and they are usually secured in their proper positions on the shoe by nails driven through the cleats and the shoe sole and clinched on the inside of the sole.

It will be understood, of course, that the cleat arrangement on the left shoe will be the reverse of that on the right shoe.

While I have shown the arrangement and construction of cleats which I prefer to use, it is contemplated that other cleat constructions can be substituted and somewhat different arrangement employed within the spirit of the invention.

Having thus described my invention, what I desire to claim as new is:

1. A football shoe having cleats of a plurality of types secured on the bottom thereof, certain of said cleats having flat sides, and the cleats of one type being interspersed

with those of the other type so that the adjacent surfaces of the neighboring cleats do not present flat faces of substantial area in opposed contiguous relationship.

2. A football shoe having a row of cleats secured to the sole near one edge thereof, said row including both circular and flat sided cleats, with the circular cleats located adjacent to and between the flat sided cleats.

3. A football shoe having rectangular and circular cleats arranged in two rows located on the sole near opposite edges thereof, the two kinds of cleats alternating with each other in each row.

4. The combination with a football shoe, of rectangular cleats located transversely on the sole of the shoe at the ball and near the extremity of the toe, additional rectangular cleats located longitudinally on the ball and toe portions of the shoe, and circular cleats located on the ball portion of the sole near opposite edges thereof between the rectangular cleats.

5. A football shoe having cleats on both the sole and heel thereof, certain of said cleats being tapered and flat sided, while others are of frusto-conical form, the two types of cleats being so arranged as to prevent the presence of flat surfaces of substantial area in opposed contiguous relationship.
